UNITED STATES PATENT OFFICE

2,160,868

TOE REST FOR SHOE MACHINES

Arthur R. Hubbard, Beverly, Mass., assignor to
 United Shoe Machinery Corporation, Paterson,
 N. J., a corporation of New Jersey

Application December 30, 1937, Serial No. 182,561

5 Claims. (Cl. 12—127)

This invention relates to shoe machines and particularly to a work rest or support and is illustrated as embodied in a toe rest for engaging the forepart of a shoe such as is employed in machines for cement-attaching soles to shoes, a machine of this type being disclosed in Letters Patent of the United States No. 2,047,185, granted July 14, 1936, upon application of Ballard et al.

In machines of this type, whether the pressure is applied by the toe rest to the forepart of the shoe or whether the toe rest sustains the shoe against pressure applied by the pad, there is danger, since the pressure is maintained for a considerable time, that the pressure will cause the rest to leave a mark or blemish upon the upper. Also, since the center of support of the toe rest is over the longitudinal center line of the last the usual bilaterally symmetrical toe rest affords no more support on one side of the shoe than on the other, whereas the area of the outside of the shoe sole with respect to the longitudinal median line is considerably greater than that of the inner side of the sole.

Objects of this invention are to provide a toe rest of simple construction which will be sufficiently yielding and of sufficient area to minimize any tendency to mark the shoe and which is bilaterally unsymmetrical so as to afford a more extended area of support on the outer side of the shoe than on the inner side, thus counteracting the tendency of the shoe to rock in response to the greater pressure applied on the outer side of the shoe. Another object of the invention is to enable the yielding portion of the support to be removed and another yielding portion substituted therefor.

These and other features and objects of the invention will appear more fully from the following description when read in connection with the accompanying drawing and will be pointed out in the appended claims.

In the drawing,

Fig. 1 is a side view of a shoe to which pressure is being applied, the toe rest embodying the present invention being shown partly in longitudinal section, and

Fig. 2 is an inverted plan view of the toe rest showing its shoe-engaging face.

Machines of the type disclosed in the patent above referred to comprise a yielding pad 10 against which the shoe is pressed, a heel abutment 12 which engages the cone of a last 14, and a toe abutment 16 carrying a toe rest which engages the upper 18 of a shoe upon the last, the sole of the shoe being represented at 20.

When pressure is applied to the shoe by movement of the abutments 12, 16, the pad 10 conforms to the shoe bottom and applies pressure to the sole and causes it to be attached to the shoe. The toe rest of the present invention, as illustrated partly in section in Fig. 1, comprises a casing 22 having on its upper face a T-guide 24 adapted to engage a corresponding T-way formed in the abutment 16 and extending transversely of the shoe. The casing 22 is held in 10 transversely adjusted position by a set-screw 26.

In the casing 22 is a rubber pad 28 shaped to fill the casing and to extend substantially beyond the lower edge of the side walls 30 of the casing. Projecting downwardly into the casing approximately centrally thereof is a ball-ended stud 32, and the rubber pad 28 is molded with a recess in its upper side corresponding in shape and location to the stud 32 so that by merely inserting the pad in the casing the hole in the pad will receive the stud 32 and the pad will be held in the casing but may be readily pried out in case it is desired to change one pad 28 for another. Pads 28 of different degrees of hardness may be provided and a pad of the proper hardness for the work in hand may be selected and placed in the casing.

It has been found that good results are obtained under usual conditions when the rubber pad 28 has a hardness of 60 to 65 durometer. 30

It is usual to provide pads of this type with leather covers and in the present instance the pad has a leather cover 34. The cover 34 is cut to proper shape to cover the shoe-engaging face and sides of the pad 28 and its marginal portions are skived and cemented to the side faces only of the pad, the portion of the cover on the shoe-engaging face of the pad being thus unsecured to the pad so that as the pad is distorted under pressure it can move relatively to the cover 40 on the face of the pad. This prevents the pad cover from becoming wrinkled, as may happen if the cover is secured to the face of the pad. It will be seen that the skived marginal portions of the cover extend up the sides of the pad far enough to be enclosed by the walls 30 of the casing so that the edges of the cover are protected and their adhesive engagement with the pad cannot be disturbed unless the pad is withdrawn from the casing. 45

Viewing the lower side of the pad, it will be seen that the pad is unsymmetrical with respect to the longitudinal median line of the last represented by the line M—M in Fig. 2; that is, the pad shown is intended for a right shoe and the 55

part of the pad below the line in the figure engages the shoe on the outer side of the longitudinal median line and, by reason of its greater area of contact with the shoe on that side, acts to apply greater pressure on that side or to sustain the greater pressure of the pad 10 against the shoe on that side of the median line, thus preventing upward tipping of the outside of the shoe in response to the greater pressure of the pad 10 on that side. The rear wall of the casing is made somewhat concave forwardly at 36 and the pad 28 is upwardly concave in the region indicated at 38, making this part of the pad correspond more closely to the shape of the last at the throat portion of the shoe which it engages. The shoe-engaging face of the pad 28 is made flat or slightly convex over a large part of its area so that as pressure is applied it will begin at the center of the pad and be gradually extended toward its sides. The corner between the sides of the pad and its work-engaging face is rounded so that when heavy pressure is applied to the pad the area of pressure does not stop abruptly at an edge of the pad but gradually fades out so that no line of demarcation is likely to be made between the part of the shoe upper which receives the pressure and the part to which no pressure is applied.

Since the pad fits the casing, only the portion of the pad which extends beyond the casing is subject to deformation by pressure and hence the deformation of the pad may be controlled by providing casings having side walls of different heights or by making the wall of less height in the region where greater deformation is desired.

Having thus described my invention, what I claim as new and desire to secure by Letters Patent of the United States is:

1. A toe rest for shoe machines comprising a

casing having side walls, a rubber pad fitting the casing and extending beyond the walls of the casing, and means located in the casing between said side walls for holding the pad in place against accidental removal but permitting it to be removed at any time by a pull applied thereto. 5

2. A toe rest for shoe machines comprising a casing having side walls, a rubber pad fitting the casing and partially enclosed by said side walls, and a ball-ended stud extending into the casing 10 and into a complementally shaped opening in the rubber pad to hold the pad detachably in place.

3. A toe rest for shoe machines comprising a rubber pad for engaging the forepart of a shoe on a last, the pad being unsymmetrical with respect to the longitudinal median line of the last and providing a greater area of contact on the outer side of the shoe, and a casing confining the major portion of the pad. 15

4. A toe rest for shoe machines comprising a casing having side walls, a rubber pad fitting the casing and extending beyond the walls of the casing, means in the casing extending into the pad for holding the pad in place against accidental removal but permitting it to be removed at any time by a pull applied thereto, and a cover for the pad, the marginal portions of the cover being reduced in thickness and secured to the pad between the pad and the side walls of the casing. 20

5. A toe rest for shoe machines comprising a 30 casing having side walls, a rubber pad substantially fitting the casing and extending beyond the walls of the casing, and a cover for the pad, said cover being loosely applied to the shoe-pressing face of the pad and having its marginal portions secured to the pad and located between the sides of the pad and the walls of the casing. 35

ARTHUR R. HUBBARD.
